CLAIM

The ornamental design for an adapter shim for kitchen sink baskets, as shown and described.

DESCRIPTION

FIG. 1 is a top, front and left side perspective view of an adapter shim for kitchen sink baskets showing my new design;

FIG. 2 is a top plan view thereof;

FIG. 3 is a front elevational view thereof;

FIG. 4 is a right side elevational view thereof, the left side being the same as the right side; and

FIG. 5 rear elevational view thereof; and,

FIG. 6 is a bottom plan view thereof.

FIG. 1

FIG. 2

FIG. 3

FIG. 4

FIG. 5

FIG. 6
